UNITED STATES PATENT OFFICE.

JAMES H. FOSTER, OF CLEVELAND, OHIO, ASSIGNOR TO THE HYDRAULIC PRESSED STEEL COMPANY, OF CLEVELAND, OHIO, A CORPORATION OF OHIO.

SKID.

1,121,912.

Specification of Letters Patent.

Patented Dec. 22, 1914.

Application filed December 11, 1908. Serial No. 466,935.

To all whom it may concern:

Be it known that I, JAMES H. FOSTER, a citizen of the United States, residing at Cleveland, in the county of Cuyahoga and State of Ohio, have invented a certain new and useful Improvement in Skids, of which the following is a full, clear, and exact description, reference being had to the accompanying drawings.

10 This invention relates to skids, which are employed to facilitate the handling of heavy objects to raise the same from a lower to a higher level and vice versa, as in the case of loading and unloading wagons, drays, etc.

It has for its objects to provide a skid which shall be of metal, and which shall be light, strong, easily assembled and disassembled to permit shipment in a knocked-down-condition; also to provide an all-metal skid which shall be extremely simple of construction and cheap of production. I accomplish these objects by the embodiment of my invention illustrated in the accompanying drawings forming a part hereof, wherein—

Figure 1 represents a perspective view of a skid constructed in accordance with my invention; Fig. 2 represents an elevation of a sheet metal blank from which one of the side members of the skid is formed; Fig. 3 represents a side member produced by bending the blank illustrated in the preceding figure; Fig. 4 represents an enlarged transverse sectional view through the skid shown in Fig. 1; Figs. 5 and 6 represent respectively an enlarged elevation and an enlarged perspective view of the opposite ends of one of the sides of the skid; and Fig. 7 represents a side elevation of one of the forgings for the hook and pointed support for the skid.

Describing now the various parts by reference characters, 1 represents the complete skid, the same comprising generally a pair of side members 2 connected by bolts 3, each side member being provided at opposite ends thereof with a hook and a pointed support, respectively, which will be described hereinafter in detail.

In constructing my skid, I provide for each side a sheet metal blank 2^a, such as shown in Fig. 2 of the drawing, the ends of said blank being tapered as shown at 2^b.

I then bend the opposite sides of the blank 55 thereby forming flanges 2^c projecting substantially at right angles from the body portion or web 2^d thereof, and producing from the blank a channel-shaped side member, as shown more particularly in Fig. 4, said 60 side member having the opposite ends thereof tapered, as shown in Figs. 1, 3, 5 and 6. The opposite ends of said side member are provided respectively with a hook 4 and a 65 pointed support 5, formed from the style of forging shown in Fig. 6. This forging comprises a body 6, which is relatively wide and thin at its inner portion and has the opposite sides thereof inclined to correspond to the inclination of the flanges 2^c at the ends 70 of the side member 2 and to fit snugly therebetween. The inner end of the body 6 is rounded. Toward the outer and narrower portion thereof, body 6 is thickened, as 75 shown at 6^a, to the full depth of flanges 2^c and is provided with a bore 6^b for the reception of a rivet. Outside of said bore, it is provided with shoulders 6^c and 6^d. Shoulders 6^c abut against the ends of flanges 2^c and shoulder 6^d abuts against the web 2^d between said flanges, the projection of said shoulders beyond the body of the forging being substantially equal to the thickness of the metal of which the side member is composed.

The style of forging shown in Fig. 7 answers, without further manipulation, for the pointed supports for the lower end of the skid. In applying such forging to the side member of the skid, the inner portion 90 thereof is fitted between flanges 2^c with shoulders 6^c and 6^d in contact with the end of said member and the forging is secured in place by rivets 7 which connect the inner portion thereof to web 2^d and rivet 8 which 95 passes through flanges 2^c and the bore 6^b. When so secured, the sides and bottom of the support constitute extensions of the tapered flanges 2^c and web 2^d.

For the hooks which are applied to the 100 upper end of the skid, I employ the same style of forging as shown in Figs. 6 and 7, merely bending the outer end of the forging transversely to the length thereof, to produce the hook shown in Fig. 5. This hook 105 has the same inner portion 6, bore 6^b and shoulders 6^c and 6^d as support 5, and is secured to what will be the upper end of side

member 2 in the same manner as 5 is applied, to what will be the lower end. The outer portion, however, is provided with the hook 4, as shown.

5 The side members 2 are placed with the flanges 2^c projecting inwardly and are connected by a suitable number of bolts 3, the number of bolts employed depending upon the length of the skid. Three such bolts are
10 shown in the drawing, but more or less may be employed, depending upon the length of the skid. The middle portions of the bolts are bowed downwardly, as will appear more particularly from Fig. 4, and the ends are
15 reduced, forming shoulders 3^a adapted to abut against the inner surfaces of webs 2^a, and such reduced portions are provided with threaded ends 3^b for the reception of nuts 9. By setting up the nuts, the side members
20 will be clamped firmly against shoulders 3^a.

From the above description, it will be apparent that I have produced an all-metal skid which is extremely simple of construction, is easily assembled, and dis-assembled,

and which is light, strong, and economical 25 of production.

Having thus described my invention, what I claim is:

A skid comprising a pair of channel-shaped side members each having tapered 30 ends, and forgings applied to said ends, each forging having a relatively thin inner portion fitted between the flanges at the end of said member and being thickened adjacent to the extreme end of said member and provided with a vertical bore, a rivet extending through said flanges and the vertical bore of each forging, one of said forgings being shaped to form a hook for the upper end of 35 said member, and the other being shaped to form a tapered support for the lower end thereof, substantially as specified.

In testimony whereof, I hereunto affix my signature in the presence of two witnesses.

JAMES H. FOSTER.
